[57] CLAIM

The ornamental design for an identification marker unit for cables, as shown and described.

DESCRIPTION

FIG. 1 is a perspective view of an identification marker unit for cables showing the front, bottom and one end of my new design;

FIG. 2 is a perspective view thereof showing the rear, top and end shown in FIG. 1;

FIG. 3 is an enlarged rear elevation view thereof in inverted condition;

FIG. 4 is an enlarged front elevation view thereof;

FIG. 5 is an enlarged end elevation view of the end shown in FIG. 1, it being understood that the opposite end is a mirror image thereof;

FIG. 6 is an enlarged bottom plan view thereof; and FIG. 7 is an enlarged top plan view thereof.

The five transversely spaced vertical broken lines shown in FIGS. 1, 2, 3, 4, 6 and 7 are understood to represent breaking points for separating the individual marking units.

The broken line showing of numerals and letters in FIGS. 1 and 4 of the drawing is for illustrative purposes only and forms no part of the claimed design.

FIG 1
